UNITED STATES PATENT OFFICE.

JOHN WILLIAM GEORGE, OF STROUD GREEN, LONDON, ENGLAND.

INTERNAL-COMBUSTION ENGINE.

1,361,978.

Specification of Letters Patent. Patented Dec. 14, 1920.

Application filed March 8, 1920. Serial No. 364,243.

To all whom it may concern:

Be it known that I, JOHN WILLIAM GEORGE, a subject of the King of Great Britain and Ireland, residing at Stroud Green, in the county of London, England, have invented a new and useful Internal-Combustion Engine, of which the following is a specification.

This invention relates to internal-combustion engines in which two or more pairs of co-axial cylinders are arranged in parallel relationship. Such pairs of cylinders are usually provided with pairs of piston heads, each pair of which is connected together by one rod passing through packing mounted between the piston heads. When four of such pistons have been arranged in one group of four of said cylinders and in one casting a pair of cylindrical valve chambers have also been provided in such casting, one of which chambers is situated on each side of the engine, in parallel relationship with the cylinders, and on a line mid-way between said cylinders. The valve chambers contain cylindrical sleeves and valves operated by the motion of the engine and the valves, chambers and sleeves all contain ports for controlling the inlet and exhaust of the gases.

The object of the present invention is to provide two or more cylinders open at their outside ends to allow for lubrication and arranged in co-axial alignment, a pair of piston heads operating in each pair of cylinders and connected together by one rod passing through adjustable packing, and explosion chambers between said piston heads and said packing.

Minor objects of this invention consist in providing an engine, as set out in the main object, with shafts arranged parallel with the axis of the co-axial cylinders and adapted to operate eccentric rods or cams for partially rotating the valve members and sleeves and split packing rings adapted to be adjusted in the manner hereinafter more particularly described.

Referring to the drawings:—

Figure 1 is a view showing one construction of the improved engine, and taken on the line *a*—*a*, of Fig. 2.

Fig. 2 is a plan view in section, and taken on the line *b*—*b* of Fig. 1.

Fig. 3 shows a modified construction of engine, and is a sectional view taken on the line *c*—*c* of Fig. 4, and,

Fig. 4 is a plan view of this modification.

In the casing *d* of both constructions of engine is provided a number of cylinders *a'*, *b'*, *c'*, *d'*, and a pair of cylindrical valve chambers *f'*, *g'*, carrying the rotary valve members *f* and *g*, respectively, and also intermediate sleeve members *h*, *i*, operated by suitably arranged and eccentrically operated valve rods *j*, *k*, *l*, *m*. In Figs. 1 and 2 of 65 the drawings the rods *j*, *l*, are shown operated by a rotating shaft *n*, and the rods *k*, *m*, are shown operated by another rotating shaft *o*, while in the other construction of engine shown by Figs. 3 and 4, all the rods 70 *j*, *k*, *l*, *m*, are operated by one shaft *p*. The shafts *n*, *o*, *p*, receive motion by any suitable means from the main crank shaft of the engine, but the shaft *p*, in Figs. 3 and 4, is shown mounted upon a bar, or the like framing *q*, which is supported from the top of the cylinder *c'*, and carries a gear wheel *r*, in mesh with the wheel *s*, mounted on the shaft *t*.

It will be noticed that all the cylinders *a'*, *b'*, *c'*, *d'*, are open at their extreme ends *a*², *b*², *c*², *d*², and that a piece of gauze *u* is arranged above the cylinders *a'*, *c'*.

The ends of the cylinders being open as shown to allow for the easy assembling of 85 parts and also for lubricant, thrown out of the cylinders during the working of the engine, to be collected on the gauze *u*, to be distributed, or returned, if over lubricated, through the passage *v* into the crank case. 90

Each cylinder is provided with suitably ringed piston heads *a*³, *b*³, *c*³, *d*³. The rod *w* connects the heads *a*³, *b*³, while the rod *x* connects the heads *c*³, *d*³.

The suitably shaped casing *d* is provided 95 between the cylinders *a'*, *b'* and *c'*, *d'* respectively with V shaped split rings which are adapted to exert pressure upon the rods *w* and *x* to form a gas tight joint.

This pressure can be obtained in many 100 ways and in the drawings I have simply shown a pair of V shaped split rings *y* and a set screw *z* the end of said set screw pressing against another V shaped split ring 105 co-operating with the split rings *y*. Thus it will be seen that by adjusting the screw *z* the pressure on the rings *y* is also adjusted. If preferred, the said screws can be shortened and coiled springs placed between the ends of the screws and the split ring acting 110 on the split rings *y*. This packing system provides a suitable gas tight joint between

the respective cylinders a' b' and c' d' and allows for the power and working strokes of the engine to take place between the inner faces of the piston heads a^3 , b^3 , c^3 , d^3 , and 5 the packing system y , z . Each of the valve members f , g , are divided as shown in Fig. 2. The compartments 1, 3 and 5 serve as inlet ports, while 2, 4, and 6 act as exhaust ports.

The divisions 7 between the compartments 10 are shaped as shown in dotted line in Fig. 1 so that gases entering at 9 are exhausted at 10 on the discharge stroke of any particular piston. It will be seen that while the valve members f , g , have six ports, one to 15 each chamber, the sleeve members h , i , and the casings f , g , have only three ports each. The arrangement is such that when a lead of 90° is given to the eccentrically operated rods controlling the sleeve members in advance 20 of the eccentrically operated rods controlling the valve members it is possible to arrange that the ports in the sleeve members and chambers are each caused to coincide alternately with an inlet port and exhaust port 25 of the valve members. Further the connecting channels 11, and 12 between the cylinders a , and c' , and valve chambers f , g , as shown in Fig. 2, are oppositely disposed to similar channels connecting the chambers of the 30 valves with the cylinders b' , d' . Thus similar strokes are simultaneously effected in opposed cylinders on all the various strokes of the engine.

By referring to the drawings it will thus 35 be seen, that by placing the four cylinders as shown with pistons acting in unison that a considerable amount of crank mechanism is dispensed with, besides a huge amount of casing, and general valve mechanism, while 40 at the same time many minor advantages are obtained.

There is no limit to the number of cylinders that could be placed in alignment, and provided on an extended scale with pistons 45 and valve mechanism of the invention as described, and in such extended principles it is possible to adapt and arrange the valve

mechanism, so that an equal number of firing strokes are obtained on the rods of a pair of pistons acting in opposed directions on 50 the same crank shaft to produce a balanced engine. The engine is suitably water jackedeted, and lubricated.

I claim:—

1. An internal combustion engine comprising 55 in combination a casing with four cylinders open at their outside ends and two valve chambers, two pairs of piston heads connected together and each of said piston heads working in one of said cylinders, adjustable packing situated between said piston heads, explosion chambers between said piston heads and said packing and valves within said valve chambers.

2. An internal combustion engine comprising 65 in combination a casing with four cylinders open at their outside ends and two valve chambers, valves within said chambers, piston heads within said cylinders, eccentric or cam controlled mechanism carried by shafts 70 arranged parallel with the axis of the cylinders for operating the valves, and sleeves carried between said valves and the inner walls of said valve chambers.

3. An internal combustion engine comprising 75 in combination a casing with four cylinders open at their outside ends and two valve chambers, two pairs of piston heads connected together and each of said piston heads working in one of said cylinders, rods connecting said piston heads in pairs, split rings around said rods, a V-shaped split ring co-operating with a pair of the aforementioned split rings and adjusted by screws supported from the casing, explosion chambers between 85 said piston heads and said packing, circular sleeves with ports operating in conjunction with ports in the valve chambers and ports in partially rotatable valves carried within said sleeves, shafts arranged parallel with the axis 90 of the cylinders and cams or eccentrics upon said shafts for operating the valves and sleeves.

JOHN WILLIAM GEORGE.
